(57) **CLAIM**

The ornamental design for a pet stair, as shown and described.

DESCRIPTION

FIG. 1 is a front perspective view of a pet stair, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a first component of the pet stair of FIG. 1, shown separately for clarity;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view of a second component of the pet stair of FIG. 1, shown separately for clarity;

FIG. 18 is a rear perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a configured perspective view thereof; and,

FIG. 26 is another configured perspective view thereof.

1 Claim, 26 Drawing Sheets
